UNITED STATES PATENT OFFICE.

ARVID BRODIN, OF LOS ANGELES, CALIFORNIA.

HAT STRETCHER.

Application filed August 1, 1923. Serial No. 654,994.

To all whom it may concern:

Be it known that I, ARVID BRODIN, a citizen of the United States, and a resident of Los Angeles, in the county of Los Angeles 5 and State of California, have invented certain new and useful Improvements in Hat Stretchers, of which the following is a full, clear, and exact description.

Among the principal objects which the 10 present invention has in view are: to provide means for stretching or varying the size of hat frames; to obtain a uniform stretching pressure at a plurality of points; to provide an apparatus as characterized, the 15 sections of which are guided in their action to obtain a more uniform pressure.

Drawings.

Figure 1 is a side view of a stretcher of 20 the character mentioned.

Figure 2 is a cross section taken on the line 2—2 in Figure 1.

Figure 3 is a top view of the invention.

Figure 4 is a vertical section, the section 25 being taken on the line 4—4 in Fig. 2.

Figure 5 is a fragmental section, the section being taken as on the line 5—5 in Fig. 1.

Figure 6 is a detailed view in section 30 showing a fragment of the head of the stretching apparatus.

Description.

The present invention has for one of its 35 principal objects to exert a stretching pressure simultaneously on a number of points or portions of the hat shape or crown rather than as heretofore on two portions of the hat band.

With this object in view, a number of 40 segments which when united form a mold having an outer shape substantially as shown in the drawings. Preferably the segments are shaped to provide a plurality of circumferential molds of different diameters such as 45 are indicated by the designating numerals 11 and 12, the former indicating the more contracted section, and the latter numeral the more expanded section.

The segments which form the mold are 50 preferably made of any suitable light weight metal. The segments have each, end extended tongues 13 which in service fit grooves 14 formed in each of the adjacent segments. The tongues 13 are disposed in 55 staggered relation as best seen in Fig. 2 of

the drawings. The tongues thus form interlocking or aligning members for maintaining the operating relation of the various segments when the same are expanded.

A similar purpose is served by the top sector 60 extensions 15 with which each of the segments is provided. The sectors 15 are arranged in pairs, one pair being assigned to each of the segments. Each pair is divided by the end-opening slot 16, opening toward 65 the center of the mold. The slots 16 are furnished to receive the splines 17 with which a relatively stationary cover 18 is provided.

The splines 17 as best seen in Fig. 2 of 70 the drawings are extended radially from the center hub 19 with which the cover 18 is provided. The purpose of the hub 19 is to receive an inner cover 20, which as seen best in Fig. 3 of the drawings completely 75 covers the sectors 15 and the splines 17. The cover 20 is secured to the hub 19 by fastening members 21 such as screws shown in the drawings.

The hub 19 forms a bearing for a pivot member 22. The pivot member 22 as shown best in Fig. 4 of the drawings has preferably a screw, the threaded end of which engages the end of the feed screw 23. The screw 23 is centrally located in the stretcher and has 80 a winged head 24 which enables the operator to manipulate the screw readily. The threads of the screw 23 engage the threads in the blocks 25 and 26 through which is imparted to the segments of the stretcher, 85 the expansive and contractive movement of said segments.

As best seen in Figure 3 of the drawings, the block 26 has bracket extensions 27 disposed in parallel relation. The bracket extensions 27 are elongated and are provided each with a pintle shaft 28, each of which serves as a pivot for the spring of the links 29.

The opposite end of each of the links 29 100 is pivotally mounted on a pin 30 in brackets 31 in the side of the segments. Each segment it will be understood has brackets 31 and links 29. It will be noticed that the walls of the brackets 27 being disposed in 105 parallel relation they operate on the links 29 as guides to hold the same in working position.

In operation the winged head 24 is first 110 turned to contract the segments so that they

enter the inside of the hat crown freely. If the hat crown fits the upper or smaller section, this only is placed within the crown. If on the other hand it fits the lower section, the stretcher is inserted within the crown until the said lower section aligns with the sweat band of the hat. The stretcher being placed in this manner, the operator manipulates the screw 23 so that the blocks 25 and 10 26 are caused to travel lengthwise of the said screw and toward the open end of the stretcher. The said blocks moving in the manner mentioned approach the outer end of the screw becoming interposed between 15 the brackets 31 to which they respectively belong, with the result that the said brackets and parts associated therewith are moved outward from the center of the stretcher.

As is seen best in Fig. 4 of the drawings, 20 the links 29 are held in parallel relation, the blocks 25 being moved by the same screw 23 at the same rate. The parallel relation of the said links is at all times maintained.

In the movement of the segments of which 25 the stretcher is composed, it will be observed, they are guided by the splines 17 which are connected to the cover 18. The cover 20 prevents the screw 23 lifting the segments of which the stretcher is formed 30 by holding the sectors 15 in position and in guided relation to the splines 17.

Claims.

1. A hat stretcher comprising a plurality 35 of form segments corresponding substantially to the shape of a hat for personal wear; a plurality of covers disposed in spaced relation, engaging portions of said segments for controlling the movement 40 thereof to and from the center of the stretcher; a screw member; and a plurality of links pivotally connected to said segments and operatively connected with said screw whereby the inner ends of said links are

caused to travel in parallel relation to the 45 axis of said screw.

2. A hat stretcher comprising a plurality of form segments shaped in correspondence with the interior of a hat of personal wear; a plurality of covers held in permanent 50 spaced relation for engaging said segments to permit the same being moved to and from the center of said stretcher; a feed screw pivotally connected with said covers; a plurality of travelling nuts mounted on said 55 screw; and a plurality of links pivotally connected each to one of said segments and to one of said nuts.

3. A hat stretcher comprising a plurality of form segments shaped in correspondence 60 with the interior of a hat of personal wear; a plurality of covers held in permanent spaced relation for engaging said segments to permit the same being moved to and from the center of said stretcher; a feed screw 65 pivotally connected with said covers; a plurality of travelling nuts mounted on said screw; oppositely disposed pairs of parallel spaced arms on each of said nuts and a plurality of links pivotally connected each 70 to one of said segments and between a pair of said arms and movable therebetween to prevent rotation of said nuts.

4. A hat stretcher comprising a plurality of formed segments, a top cover plate, a hub centrally disposed on said plate, a bottom plate attached to said hub and disposed throughout its major portion in parallel spaced relation to said top plate, sectors 75 formed on said segments and slidable between said plates, a feed screw pivotally connected to one of said cover plates, a plurality of traveling nuts disposed on said feed screw and link connection between said 80 nuts and segments for moving said segments 85 on rotation of said screw.

ARVID BRODIN.
